UNITED STATES PATENT OFFICE.

WILLIAM G. KENDALL, OF NEWARK, NEW JERSEY

HINGE FOR BOXES AND THE LIKE.

1,236,845.

Specification of Letters Patent. Patented Aug. 14, 1917.

Application filed November 2, 1916. Serial No. 129,163.

To all whom it may concern:

Be it known that I, WILLIAM G. KENDALL, a citizen of the United States, residing at Newark, in the county of Essex and State 5 of New Jersey, have invented certain new and useful Improvements in Hinges for Boxes and the like, of which the following is a specification.

My invention relates to new and useful 10 improvements in boxes and like containers, the primary object of my invention being the provision of an improved form of hinge particularly adapted for use in connection with boxes made of light sheet metal having 15 hinged covers, such boxes being commonly employed as vanity boxes.

One of the chief objects of my invention consists in the provision of an extremely 20 simple form of hinge which may be stamped or otherwise formed from sheet metal and readily applied to the box and cover.

Another object of my invention consists 25 in constructing a hinge of this character which will hold the cover closely to the box when the cover is closed and which will support the cover at right angles to the box when swung to open position.

In this connection, a still further object of 30 my invention consists in constructing a hinge of such a type that the hinge is only fixed to one of the two members to be connected, the remainder of the hinge operating through a slot formed in the other member.

In this connection, a still further object 35 of my invention consists in constructing a hinge which is wholly or principally formed in a single piece.

With these and other objects in view, my invention will be more fully described, illustrated in the accompanying drawings, and then specifically pointed out in the claims which are attached to and form a part of this application.

In the drawings:

40 Figure 1 is a perspective view of a box provided with a hinge constructed in accordance with this invention, the box being in closed position;

Fig. 2 is a central vertical sectional view 45 taken through the box and hinge;

Fig. 3 is a view taken at right angles to Fig. 2, a portion of the box being broken

away to show the manner of connecting the hinge to the cover;

Fig. 4 is a perspective view of the cover 55 with the hinge detached;

Fig. 5 is a view corresponding to Fig. 1, illustrating a modified form of my invention;

Fig. 6 is a view corresponding to Fig. 2, 60 showing the form of invention disclosed in Fig. 5;

Fig. 7 is a perspective view of the cover with the modified form of hinge;

Fig. 8 is a fragmentary view, illustrating 65 the form of hinge shown in Fig. 7 as an integral portion of the cover.

Corresponding and like parts are referred to in the following description and indicated in all the views of the drawings by 70 the same reference characters.

In order to insure a clear and accurate understanding of my invention, I have illustrated my improved hinge, indicated as a whole by the numeral 10, in connection with 75 a box 11. This box 11 includes a bottom 12 and an upstanding peripheral wall 13 formed in spaced relation to its upper edge with an outstruck annular stop bead 14. The cover 15 is formed with a depending 80 annular flange 16 adapted to engage about the upper portion of the wall of the box and in closed position to seat against the bead 14.

The hinge 10 includes a substantially rectangular shaped body of sheet metal provided at one end with a hinge bar or wire 17 of greater length than the width of such end of the plate and curved to conform to the inner curvature of the peripheral wall of the box. The opposite end portion of the 90 body or plate of the hinge is formed with a plurality of V-shaped clefts 18 to define a plurality of anchoring prongs or tongues 19. In applying the hinge, the peripheral wall of the box at the bead is formed with a slot 95 20 of sufficient width for the passage of the body portion of the hinge and the peripheral flange of the cover is formed with slots 21 for the passage of the tongues 19. The body portion of the hinge is passed outwardly through the slot of the box to seat the locking bar 17 in the bead, the locking tongues 19 are passed inwardly through the slots of the cover and such tongues are then

bent against the inner face of the cover flange to secure the hinge thereto. Preferably, three tongues are provided, arranged in the manner shown in Fig. 3, and are bent so that one of the tongues is directed toward the others so that certain tongues will resist displacement of the hinge against strain in one direction, while certain other tongues will resist opposite strain.

10 As will be appreciated, by reference to Fig. 2, when the cover is closed, the body of the hinge is drawn upwardly so that the locking bar or wire 17 engages against the inner face of the wall of the box and serves 15 to hold the cover closely in place. When the cover is swung to open position, the free ends of this bar engage the wall of the box to support the cover at substantially right angles to the body.

20 In Figs. 5, 6 and 7, I have illustrated a modified form of invention in which the box structure, being identical with that shown in Figs. 1 and 2, has its parts indicated by like numerals. In the form there shown, the 25 flange 16 of the cover is outpressed to provide a substantially rectangular internal seat 22 of such depth as to be capable of seating the body portion of the hinge, indicated as a whole by the numeral 23. This hinge 30 is formed from a single piece of sheet metal, being stamped out by any suitable die and its body portion is provided with V-shaped clefts 24 defining locking tongues 25 which are passed outwardly through the flange of 35 the box cover and bent over, as shown in Fig. 5, to secure the hinge to the cover. The free end of the hinge is bent inwardly at a slight angle to the body of the hinge and is passed inwardly through the slot 20 of the 40 wall of the box. The corners of this free end are inbent slightly, as shown at 26, so as to in no way interfere with the closing of the cover and that portion of the hinge projecting through the slot 20 is formed with 45 a U-shaped cleft to provide a locking tongue 27 having its free end directed upwardly. When the hinge has been applied to the cover and box, the free end of this tongue is sprung inwardly to the position shown in 50 Figs. 6 and 7.

As shown in Fig. 6, the free end of this tongue 27 together with the body of the hinge wedge the edge of the box wall forming the upper portion of the slot 20 when 55 the cover is closed so that all tendency for the hinge side of the cover to move away from the box is prevented. Upon moving the cover to open it, the free end of the tongue 27 acts as a fulcrum against the inner face of the box wall to draw the adjacent portion of the hinge body through the slot until the edge of the flange 16 engages against the wall of the box body when further movement of the cover will be prevent-

ed. At this point, the cover occupies a position at substantially right angles to the box. Obviously, the locking bar or wire 17 may be in the form of a piece of wire soldered to the hinge body or it may be formed integrally with the hinge body.

Furthermore, it is obvious that the form of hinge first described may be formed as an integral part of the box cover flange, as clearly shown in Fig. 8 in connection with the box cover 29, the hinge proper being indicated by the numeral 31.

Although I have illustrated and described my improved hinge structures in all their details, it will be appreciated that I do not wish to be limited to the specific details of 80 construction illustrated and described, but reserve the right to make any changes which may fall within the scope of the appended claims.

Having thus described the invention, what 85 is claimed as new is:

1. The combination with a container having a peripheral upstanding wall and a cover having a peripheral flange engaging about the wall, of a hinge plate secured to the 90 flange of the cover and projecting through a slot in the wall of the box, said hinge plate being substantially rectangular in shape and that portion within the box being formed with a substantially U-shaped cleft defining 95 an upwardly directed tongue, said tongue being bent inwardly to prevent withdrawal of the hinge plate from the container.

2. The combination with a container having a slot, of a cover, and a hinge member 100 carried by the cover and projecting through the slot, said member within the slot being struck out within its margin to provide an inwardly and upwardly directed tongue to prevent its withdrawal from the container.

3. The combination with a container having an upstanding wall formed with a slot, and a cover having a flange engaging the wall, of a hinge member carried by the flange and projecting through the slot, said 110 hinge member being formed with a substantially U-shaped cleft defining an upwardly directed tongue inbent to prevent withdrawal of the hinge member from the container.

4. The combination with a container having an upstanding wall, and a cover having a flange engaging the wall, of a hinge plate projecting from the flange of the cover through a slot in the wall, said hinge plate being substantially rectangular in shape and having its free terminals inbent after insertion through the slot, and an upwardly directed tongue struck out from the hinge plate and bent inwardly after such plate has been inserted through the slot.

5. The combination with a container having a peripheral wall and a cover having an

annular flange to engage about the wall, of a seat formed in the flange, a hinge plate engaging at one end in the seat and projecting from the flange, prongs struck out from the hinge plate and passed through the seat forming portion of the flange and bent over to secure the hinge plate in the seat, the projecting end of the hinge plate being adapt-

ed to pass through a slot formed in the wall of the container, and means carried by said projecting end engaging the wall of the container to prevent withdrawal of the hinge plate therefrom.

In testimony whereof I affix my signature.

WILLIAM G. KENDALL. [L. S.]
